UNITED STATES PATENT OFFICE.

ARTHUR F. POOLE, OF CHICAGO, ILLINOIS, ASSIGNOR, BY MESNE ASSIGNMENTS, TO
WILLIAM R. HEATH, OF BUFFALO, NEW YORK.

ACCOUNTING SYSTEM.

1,084,660.

Specification of Letters Patent. Patented Jan. 20, 1914.

Application filed June 11, 1908. Serial No. 437,376.

To all whom it may concern:

Be it known that I, ARTHUR F. POOLE, a citizen of the United States, residing at Chicago, in the county of Cook and State of Illinois, have invented certain new and useful Improvements in Accounting Systems, (Case 1^a), of which the following is a full, clear, concise, and exact description, reference being had to the accompanying drawings, forming a part of this specification.

My invention relates to an electro-mechanical system of accounting for automatically taking care of an employee's time and wages.

15 In particular my invention comprises a system of accounting in which the individual wage- and time-registers are actuated by a step-by-step movement, this actuation being controlled by electro-magnetic means. However, the totalizing registers connected with certain of the individual registers are operated through the medium 20 of differential gearing which properly connects each totalizing register with its corresponding individual registers.

Furthermore, my invention contemplates a system whereby the particular rate at which a certain individual register shall be operated may be freely selected by simply 30 inserting a connecting plug in any particular jack. The insertion of an employee's plug in any one of a series of jacks will, at predetermined intervals, cause the closing of a circuit through the corresponding register-operating devices, to control the actuation 35 of the registers associated with such devices.

In order to make provision for a number of different rates at which any given register may be operated, I employ a series of rate-disks mounted upon a time-controlled shaft. Each of these disks is provided with a peculiarly grooved periphery in which engages a contact-closing device, so arranged 45 that the rotation of the disk with which it is associated will cause movement of the device to one side or the other for the closing of the circuit which causes the operation of the electro-magnetic devices that actuate the 50 registers. Just how this is effected will become apparent when the description of the drawings is taken up in detail.

These and other objects and advantages of my invention will become apparent as the 55 specification proceeds.

In the accompanying drawings, wherein like reference characters are used to indicate corresponding parts, Figure 1 is a diagrammatic representation of one practical embodiment of my system, Fig. 2 represents in detail the register-actuating device, Fig. 3 is a side view, as appearing when looking in the direction of the arrow associated with Fig. 2, of the series of these register operating devices arranged upon a common shaft, Fig. 4 shows in detail a register operating device constructed to actuate its associated register in a direction opposite to that in which the device indicated in Fig. 2 actuates its register, Fig. 5 is a fragmentary detail view, partly in cross-section, showing a convenient form of differential gearing used in connection with the totalizing registers, Fig. 6 is a fragmentary view showing a development in plan of the periphery of one of the rate disks, and Fig. 7 shows a rearrangement of certain portions of the circuits in the diagram of Fig. 1. The object and purpose of this arrangement will be described later on.

In order that the operation of the system as illustrated in Fig. 1 may be more readily understood, I will first take up the description in detail of the register operating devices as illustrated in Figs. 2, 3, and 4.

Referring particularly to Fig. 2 and to the first (or third) of the devices shown in Fig. 3, it will be noted that the ratchet wheel 1 is loosely mounted on the shaft 2. This shaft, of course, is, at its ends, mounted in suitable bearings in the casing inclosing the parts, the lengths of the shaft being determined by the number of register operating devices which it is desired to employ. Rigidly secured to the ratchet wheel is the gear wheel 3 so that the two wheels may be rotated together as one. As shown most clearly in Fig. 5, a pinion 4 is mounted centrally in its composite wheel formed by the ratchet wheel 1 and the gear 3. Sleeves 5 and 6 are loosely mounted upon the shaft 2 upon opposite sides of the composite gear and ratchet wheel, and at their adjacent ends are provided with bevel gears 7 and 8 respectively, which engage with the bevel pinion 4, just referred to. The opposite ends of these sleeves are, of course, likewise provided with bevel gears 9 and 10, which are adapted to engage with the associated bevel pinions mounted in the corresponding gear 105 pinions mounted in the corresponding gear 110

and ratchet wheels. This showing has not been made in Fig. 5 for the reason that it would simply be a duplicate of the differential gearing therein illustrated. In the instance shown, the gear and ratchet wheels are secured together by means of screws or bolts 11, which at one end carry lugs or projections 12. The purpose of these lugs will be presently set forth.

As seen from Figs. 2 and 3 the gear wheel of each register operating device is adapted to mesh with a gear wheel 13 mounted upon a countershaft 14, suitably supported. This gear wheel 13 engages with a gear 15, which, in turn, is operatively connected with the first of a series of properly interconnected indicating wheels 16, 17 and 18, as clearly shown in Fig. 3. An electro-magnet 19 is mounted in appropriate relation to the ratchet wheel. Pivoted to the frame 20 of the support for the electro-magnet is the armature 21 which, at its outer end, carries the ratchet actuating pawl 22. This pawl is loosely pivoted on the armature 21 and is by gravity held against the teeth of the ratchet, as indicated in Fig. 2. A second electro-magnet 23 is mounted in proximity to the ratchet wheel in the relation shown in Fig. 2. This electro-magnet 23 is polarized and its windings are in series with the windings of the electro-magnet 19. This series arrangement of the windings of the two electro-magnets is indicated in Fig. 2 by the wire connection 24. The armature 25 of electro-magnet 23 is pivoted to a suitable framework at 26, and is provided with an arm or extension 27. The lower end of the armature 25 is provided with an adjustable counter-weight 27'.

A sufficient number of parts of the register operating device has now been described to afford an understanding of the operation of the device. Supposing, now, that the circuit through the electro-magnets has been closed so that the same will be energized, this momentary energization of the electro-magnet 23 will cause the armature 25 to be rocked so that the lower end will be drawn against its associated pole piece of the electro-magnet. With the armature in this position the center of gravity will, by virtue of the counter-weight 27' have been thrown to the right of the pivot 26. This rocking of the armature will lift the arm 27 upwardly out of the path of the top lug 12. At the same moment that the electro-magnet 23 is energized, the electro-magnet 19 will also be energized and in attracting the lower end of its armature 21 will cause the same to be rocked into the position indicated in dotted lines in Fig. 2. This will cause the actuating pawl 22 to drop into the next lower tooth. When the circuit through the windings of the electro-magnets is interrupted at the next moment, the extension 21' of

the armature 21 will be forced to the left through the action of the spring 28, thereby causing the pawl 22 to move the ratchet wheel one tooth to the left, that is to say, in the direction indicated by the arrow. The de-energization of the electro-magnets will not affect the position of the armature 25 for the reason that gravity will retain it in the position to which it was moved when the first energization of the electro-magnet 23 took place, so that during the successive energizations of the electro-magnet 19, the arm 27 will remain out of the path of the lugs 12, except as hereinafter specified.

Movement of the ratchet wheel in a direction contrary to that indicated by the arrow is prevented by the retaining pawl 29 pivoted to a suitable support at 30. This pawl is kept by gravity in the path of the teeth of the ratchet wheel, and while it permits movement of the same in the direction indicated by the arrow, it positively prevents rotation in the opposite direction, as may be clearly gathered from what is shown in Fig. 2. Now it may be necessary at certain times to decumulate the register, that is to say, to bring it back to zero. In this event, it is, of course, necessary that the ratchet wheel be allowed to rotate in the direction opposite to that indicated by the arrow in Fig. 2. To provide for this contingency I have arranged a rod 31, slidably mounted in a framework 32, and provided at its outer end with a manipulating knob 33. The lower or inner end of this rod has secured thereto a peculiarly shaped extension 34. The arm 35 of this extension engages at its free end a lug 36 on the arm 27 of the armature 25. The arm 37 of this extension engages at its free end a lug 38 on the actuating pawl 22. The central projection 39 of this extension 34 has a slot 40 at the bottom of which rests a lug 41 on the retaining pawl 29. This lug and slot engagement between the rod 31 and the retaining pawl 29 permits the latter to ride over the teeth of the ratchet wheel. When the rod 31 is pulled up, it will carry with it the arm 27, retaining pawl 29, and actuating pawl 22, all by virtue of the engagement between the extension 34 and the lugs on those parts. In other words, when the rod 31 is moved upwardly, the arm 27 is moved out of the path of the projections 12, the retaining pawl 29 is moved out of the path of the ratchet wheel, as is also actuating pawl 22. With the parts in this condition it is plain to see that the ratchet wheel is free to move in a direction to permit decumulation of the associated register.

In order that the rod 31 may not be accidentally moved from one position to the other, I supply a retaining means in the shape of a wedge shaped block 42 on the rod and a co-operating spring 43 mounted on the support 32. With the rod in the position

shown in Fig. 2, it will be seen that the tendency of the spring 43 is to hold it in that position; while with the rod in its drawn out position, the spring 43 will engage with the opposite side of the wedge shaped block 42 and tend to retain the rod in its drawn out or elevated position. The movement of the extension 21' of the armature 21 is limited by the lugs 44 and 45 secured to a suitable support. From this description of the construction and operation of the register actuating device, it will be seen that at every interruption of the current sent through the winding of electro-magnet 19, the ratchet wheel will be moved a distance of one tooth, and, of course, the associated register will be actuated correspondingly.

Now, the rate of actuation of the register associated with the particular actuating device, will, of course, depend upon the number of circuit interruptions that occur in a given time. The means for causing a predetermined number of current interruptions to take place in a given time through the windings of the register operating device is shown in Fig. 1, and comprises a series of what I term "rate disks" 46, 47, and 48 mounted upon the time controlled shaft 49. It will be observed that each of these disks is provided with a periphery that is grooved in a peculiar manner. In order to understand best the purpose and object of the outline of the peripheral groove on each disk, attention is directed to the illustration given in Fig. 6. The distance indicated by the dotted line 46' represents the developed periphery of the rate wheel or disk 46. Looking at the groove or channel bounded by the line 46', it will be seen that there are three upwardly projecting portions 46a. Of course when I say "upwardly" I use the term with reference to Fig. 6 only, it being understood that the direction in which these projections extend depends upon the direction in which the disk is viewed. Following these three upward projections in the peripheral groove or channel of the disk 46 is a series of seven projections deviating in a direction opposite to that of the projections 46a. For the present it is sufficient to say that each one of these projections or deviations, as they might as well be called, in the groove of disk 46 represents an approximately momentary closing of the circuit through the windings of the electro-magnets 19 and 23. However, inasmuch as deviations 46a are in a direction opposite to that of the deviations 46b, it will be apparent that the first three current impulses sent through the windings 19 and 23 will be opposite to the seven succeeding current impulses, but inasmuch as the electro-magnet 19 is a non-polarized one, the particular direction of the current traversing this winding has no effect

upon its attraction of the armature 21. This, however, is not the case with the polarized electro-magnet 23. Starting with the first current impulse, the energization of the magnet 23 will be such that the armature 25 will be rocked to cause the lower end thereof to be drawn against the attracting pole, as already mentioned. The second and third impulses through the electro-magnet 23 will not disturb the position of the armature brought about by the first impulse, for the reason that the tendency of these second and third impulses would be to draw the armature into the same position into which it was drawn by the first impulse. However, the fourth impulse, which in Fig. 6 may be said to be represented by the first of the downwardly extending deviations 46b, will rock the armature 25 into the position indicated in Fig. 2. Inasmuch as the succeeding impulses, namely impulses 5 to 10 inclusive, are in the same direction as the fourth impulse, the armature 25 will remain in the indicated position and leave the arm 27 in the path of the lugs 12.

As indicated in Fig. 6 where the distance marked off by line 46' includes the developed periphery of the disk 46, after the tenth current impulse has been sent through the electro-magnets of the register operating device, the next impulse will be the one represented by the first of the deviations 46a. This means that after ten current impulses (which, of course, are essentially accompanied by corresponding current interruptions) have been sent out into the windings of the electro-magnets, the eleventh impulse would be identical, so far as graphic representation is concerned, with the first impulse represented by the first of the three deviations 46a. From this it might truly be said that ten current impulses, (or ten current interruptions) constitute what might really be termed a "cycle". I find this term not only to be correct in properly expressing the current impulses or interruptions, but I find it convenient to explain how the other rate wheels or disks produce different rates of operation of the corresponding registers. For the sake of presenting a concrete illustration it might be supposed that the disk 46 actuates its corresponding register at a rate which represents five cents an hour, which the corresponding wage register would indicate. If, therefore, disk 46 represents a five cent rate and the number of current interruptions caused by the disk during one rotation thereof is equal to ten, or one cycle, it is plain to see that the disk 47, if it is to represent a ten cent rate, must have a periphery so grooved that it will cause during one rotation thereof, twice the number of current impulses or interruptions to be sent through the windings of the particular register actuating device. By looking at Fig. 1

it will be seen that the deviations in the peripheral groove of the disk 47 are more frequent than the deviations in the grooved periphery on the disk 46. Although the entire 5 grooved periphery has not been shown, yet the part that is shown is intended to show the number of deviations necessary to make the disk represent double the rate of disk 46. The fragment at the right of Fig. 6 is intended 10 to represent, in conjunction with the adjacent fragment, a development, partly broken away, of a disk representing a higher rate than that represented by disk 46. Disk 48 has been assumed to represent a fifteen 15 cent rate. In order to do this it will be clear that the disk must cause three times the number of current interruptions caused by the disk 46, or, to put it in the phrase of cycles, the grooved periphery of disk 48 must 20 represent three cycles if it is to have a rate three times that of the disk 46, the latter representing but one cycle, as already pointed out. Of course the five, ten and fifteen 25 cent rates have been chosen in this instance merely for the sake of illustration and any convenient ratio of rates may be adopted. To do this it is merely necessary to make the proper arithmetical calculations with respect 30 to the number of deviations in the grooved peripheries on the several disks. Mounted on the time controlled shaft 49 is also the time disk 50 which is similar in construction to the rate disks. As will be seen from Fig. 1, the grooved periphery of this time disk 35 is identical with the grooved periphery on the disk 47. This is purely a coincidence and is the result of the assumptions of the different rates to be represented by the rate disks, together with the assumption of a certain 40 speed at which the shaft 49 is to be driven. To put it concretely—for the sake of illustration I have assumed that the time shaft makes one revolution in $\frac{1}{10}$ ths of an hour. For convenience I have adopted $\frac{1}{10}$ of an 45 hour as the unit of time, and a five cent rate as the unit of wages, or in other words, the unit of time and the unit of wages are each represented by a cycle, that is to say by ten current impulses or interruptions. Inasmuch 50 as the time shaft represents in one revolution two units of time, disk 47 will represent two units of wages because each of these disks represent two cycles. It is for this reason, therefore, that in the instance shown, 55 the number of deviations on the periphery of the time disk is the same as the number of deviations on the periphery of the rate disk 47. Upon other assumptions to start with than those above mentioned, the time disk will, of course, have its own peculiar 60 number of deviations.

In connection with the detailed construction of the register operating devices there remains to be described the object and purpose 65 of the electro-magnet 23, the arm 27

on whose armature is, at certain intervals, in the path of the lugs 12 on the ratchet wheel, as indicated in Fig. 2. This mechanism has to do with the maintenance of effective synchronism between the various 70 registers and their actuating mechanisms, and between these devices and the clock controlled source of impulses. The principles of operation and the mechanism employed for this purpose are disclosed in my 75 United States Patent No. 708,253, issued September 2, 1902. It will be observed that there are four of these lugs 12, spaced at equal intervals. The number of teeth on the ratchet wheel 1 is 32 so that eight teeth 80 will occur in the arc comprehended by any two adjacent lugs. In order to operate properly it is of course necessary that the ratchet wheel be moved one tooth at every current interruption, but it might be, for some 85 reason or other, that this proper operation does not take place. In order, therefore, that there may be synchronism between the speed of rotation of the shaft 49 and the step by step movement of the ratchet disk, I have 90 provided a synchronizing arrangement in the shape of the electro-magnet 23 and its appurtenances. In order to understand how the electro-magnet effects such synchronism let it be assumed that the parts as shown in 95 Fig. 2 are ready for operation upon the beginning of a cycle of impulses. The first impulse sent through the windings 19 and 23 will, as already mentioned, rock the armature 25 to move the arm 27 out of the path 100 of the engaging lug 12. At the same time electro-magnet 19 will attract its armature 21 and cause the actuating pawl 22 to slide into engagement with the next lower tooth. Upon interruption of this momentary impulse 105 the wheel will be moved one tooth. The second and third impulses being in the same direction as the first, the arm 27 will remain in its raised position, whereby the uppermost projection 12 will have had a 110 chance to slip past the arm to the left. Now, if the actuating pawl 22 has moved the ratchet wheel one tooth ahead at every current interruption, then upon the eighth interruption the right hand projection 12 115 shown in Fig. 2 will be in the exact position in which the uppermost projection 12 was at the beginning of the cycle of operation. Of course, inasmuch as the fourth impulse of the cycle caused the armature 25 to 120 be attracted to the position in which it is shown, the arm 27 will be in the path of the lugs 12 during the period in which impulses 4 to 10 occur. Therefore at the eighth impulse, the lug 12 will have traveled through 125 an arc of 90° and abut against the free end of the arm 27. Suppose, however, that for some reason eight current interruptions have caused the actuating pawl 22 to move the ratchet wheel only seven teeth. In this event 130

at the eighth interruption the projection 12 will be the distance of one tooth away from the end of the arm 27, and in order to bring it into direct engagement with said arm, in 5 other words, in order to make it complete its travel through an arc of 90° a ninth impulse will be necessary. From this it will be seen that the ninth and tenth impulses of each cycle are what might be termed "emergency" impulses, which serve to operate the ratchet wheel only in case one or more of the first eight impulses has failed to produce operation of the ratchet wheel. Of course if the first eight impulses have caused the actuating pawl to move the ratchet wheel 10 through a distance of eight teeth, (in which event any one projection 12 will have traveled through an arc of 90°), the ninth and tenth impulses will be lost so far as producing operation of the ratchet wheel is concerned. This is due to the fact that under 15 normal conditions, the projection 12 will at the eighth impulse be brought against the obstructing end of the arm 27. By thus making sure that every cycle represented on the disks 46, 47, 48 and 50, will cause the ratchet wheel of any particular register operating device to be moved through a distance of eight teeth, I establish synchronism between 20 the rotation of the time controlled shaft 49 on which the disks are mounted and the actuation of the ratchet wheel of each register operating device.

It will be readily apparent from Fig. 5 25 where a convenient form of differential gearing is shown, that if the ratchet wheel shown in said figure is normally actuated to move in a direction away from the observer, the ratchet wheel whose pinion engages the bevel gear 10 must move in an opposite direction, or, in other words, if the first of a series of register operating devices is actuated, in a certain direction, the succeeding device will have to be actuated in an opposite 30 direction, while the next succeeding device will, of course, be actuated in the same direction as the first one of the series. As just explained, this movement in opposite directions of each pair of succeeding register 35 operating devices is, in this instance, necessary by virtue of the differential gearing that connects the ratchet wheel of one device with that of the next device in the series.

The construction shown in Fig. 4 is for 40 the register actuating devices so modified from that shown in Fig. 2 that they will normally operate in the direction indicated by the arrow, and which direction, as will be observed, is contrary to that indicated by 45 the arrow in Fig. 2. Inasmuch as certain of the parts in Fig. 4 are identical in structure and operation with certain of the parts in Fig. 2, it will not be necessary to describe Fig. 4 with such minute detail as was referred to in connection with Fig. 2. It will

be noted that in Fig. 4 the arm or extension 21a which carries the armature portion 21b is pivoted at 21c so that upon energization of the magnet, arm 21a will be rocked to the left into the position indicated partly by 70 dotted lines. This movement of the arm 21a to the left will allow the actuating pawl 22' to ride over the periphery of the ratchet wheel into engagement with the next tooth on the left. Upon deenergization of the 75 magnet the spring 28' will draw the arm back to the right into the position in which it is indicated in Fig. 4. This movement of the arm 21a to the right will cause the pawl 22' to drag with it the ratchet wheel through 80 the distance of one tooth. It will be noted that the forward end of the pawl 22' carries a projection 22a at its forward end, which fits into the recess of two adjacent teeth. Backward movement of the ratchet 85 wheel is prevented by the retaining pawl 29' pivoted at 30'. In order to cause the proper projection 12 to rest against the obstructing end of the arm 27' at the eighth circuit interruption of the cycle, I have given this end of the arm 27 the shape indicated at 27a in 90 Fig. 4. It will be seen that this downwardly projecting portion 27a constitutes a barrier to the further travel of the associated projection 12 when the two parts have arrived 95 in engagement with each other. A rod 31' similar to the rod 31 is provided to lift the arm 27', retaining pawl 29' and actuating pawl 22' out of engagement with their co-operating parts of the ratchet wheel. The 100 peculiarly shaped extension 34' has its slotted arm 35' loosely connected with a lug on the retaining pawl 29'. The central portion 36' of the extension 34' is provided with a slot engaging a lug on the arm 27'. The laterally extending arm 37' on the extension 105 34' engages at its free end a lug on the actuating pawl 22'. It will thus be seen that raising the rod 31' will remove the arm 27', and the pawls 29' and 22' from engagement 110 with the correspondingly co-operating portions of the ratchet wheel.

Referring to the mechanism for driving the shaft 49' at a resultant uniform speed, I connect the motor 51 with the shaft 49' 115 through a series of reducing gears 52. The shaft 49 is connected with the shaft 53 through a set of differentials 54. The shaft 53 is adapted to be directly actuated by a master clock 55. The motor is fed from the mains 56, and with the resistance 57 short-circuited will rotate at a higher rate of speed than the shaft 53. In this case the central wheel of the set of differentials 54 will rotate in a direction toward the observer. When the projection 58 on said wheel strikes the spring contact 59, it will move the same to the left, thereby forcing it out of contact with the terminal 60. This 120 opens the short-circuit around the resist- 125

6
ance 57 and causes the motor to slow down by virtue of the resistance 57 being placed in the circuit. With the motor thus slowed down, the shaft 49 will rotate at a lower speed than the clock driven shaft 53, with the result that the central wheel of the differentials 54 will rotate in the opposite direction, thereby moving the projection 58 away from the spring blade 59 and closing the short-circuit around the resistance 57. This will cause the motor to speed up again and rotate the shaft 49 at a higher speed than the speed of the shaft 53. Of course it will be understood that although the shaft 49 will rotate at speeds that are now higher than the uniform speed of the shaft 53, yet the resultant rotation of the shaft 49 will be the same as the rotation of the shaft 53, thereby producing rotation of the disks 46, 47, 48, and 50 at a uniform rate of speed.

I will now describe in detail the operation of my system as represented in the embodiment shown in Fig. 1. Associated with the grooved peripheries of disks 46, 47, 48, and 50 are spring contacts 61, 62, 63, and 64, respectively. The free ends of these contacts engage in the peripheral grooves on these disks, and as the disks are rotated these contacts are moved to one side or the other, according to the deviations in the grooves. When spring contact 61 is moved to the left, it engages contact 65, and when moved to the right it engages contact 66. Similarly, a pair of contacts 67 and 68 are associated with the spring blade or contact 62, a pair of contacts 69 and 70 are associated upon opposite sides of the contact 63, and finally a pair of contacts 71 and 72 are associated with contact 64. It will be observed that contacts 69, 67, 65 and 71 are all connected with the conductor 73 which leads to one terminal of the battery 74. The contacts 72, 66, 68 and 70 are all connected with the conductor 75 which leads to the opposite terminal of the battery 74. The battery is, for convenience, shown grounded at 76. Contact 64 of the time disk 50 is connected with conductor 77, to which are connected all the tip contacts 78 of the series of jacks shown. The contact 63 is, by means of the conductor 79, connected with the conductor 80. To this conductor are connected the three sleeve contacts 63'. The contact 61 is connected by means of conductor 81 with conductor 82 which has connected thereto the three sleeve contacts 61'. Contact 62 is connected by conductor 83 with conductor 84 which has connected thereto the three sleeve contacts 62'. It will thus be seen that the series of nine jacks, shown in the figure, is divided into three groups of three jacks each. Of course it will be understood that this precise number in the series and the division into a certain number of groups is purely arbitrary, it having been resorted to in this in-

stance solely as a matter of illustration. In order to avoid unnecessary multiplication of circuits in Fig. 1, I have confined myself to setting forth an embodiment of my invention as it would be used in the case of three workmen or employees whose time and wages are to be taken into account. The number of jacks in the series, of course, depends upon the number of employees of whose time and wages the system is arranged to take care. The number of groups into which the series of jacks is divided depends upon the number of different rates at which workmen are employed in any particular factory or place of employment. Inasmuch as I have selected three different rates, the series of jacks is naturally divided into three groups, each group representing a particular rate. Thus, for instance, the first group of jacks whose sleeve contacts are indicated by 62' represents the rate of the wheel 47. In the particular instance given this would be a ten cent rate. The group of jacks whose sleeve contacts are indicated by 61' represents the rate of the disk 46. Finally the group of jacks whose sleeves are indicated by 63' represents the rate of disk 48. Suppose now that the plug *a* has been inserted as shown. In this case the wage register that will be actuated because of the insertion of the plug will operate at the rate represented by wheel 47. The circuits may be traced as follows: For the sake of convenience we start at the ground 76, through the right half of the battery, through conductor 75, into conductor 75' to the point 75''. At this point, assuming that the position of the disk is such that the spring blades 64 and 62 will be forced to the right into contact respectively with 72 and 68, the current divides as follows: A portion flows through contact 68, across the contact 62 into conductor 83, into conductor 84, thence to the sleeve-contact 62', from there into conductor 85, through the wage register *Aw*, into conductor 86 to the point 87. If the workman's switch 88 is closed, the current will find ground through conductor 89 at 90. The circuit as thus traced will actuate the wage register *Aw*. The other portion of the current which divided at the point 75'' will flow as follows: into conductor 75' to contact 72, over to contact 64, to conductor 77 to the tip contact 78, thence into conductor 92, through the time register *At*, conductor 91, through the workman's individual time register *A* and from there to the ground through 89 and 90. This last traced circuit, it will be noted, will actuate the workmen's individual time register *A* as well as the corresponding time register *At*.

In order to trace the circuits completed by the plug *a* when the time shaft is in such a position that the spring blades 64 and 62 are forced to the left into contact respec-

tively with 71 and 67, let us begin as before with the ground 76, thence through the left half of the battery, through conductor 73 to the point 73'. Here the current divides, a portion of it being traced through conductor 73'', contacts 67 and 62, conductor 83, conductor 84, sleeve terminal 62', conductor 85, wage register Aw, conductor 86, switch 88, thence to the ground through 89 and 90. The other portion of the current from the point 73' is traced through contact 71 and 64, conductor 77, tip contact 78, conductor 92, time register At, conductor 91, workmen's individual time register A, thence through switch 88 and conductor 89 to ground 90. From this it will be seen that this last set of circuits is substantially identical with the first set of circuits traced, the only difference being in the portions of the circuits passing through the spring contacts 64 and 62, which contacts are moved either to the left or to the right, according to the position of the rate disks, and the time disks. From what has been explained before with regard to the configurations of the grooves on the peripheries of the time disks and the rate disks, it will be observed that during one cycle the contacts will be moved first three times to the right, then seven times to the left. From the tracing of the above circuits it will be clear what the circuits would be if plug b or plug c were inserted in the jack in which plug a is shown inserted in Fig. 1. Of course if we imagine plug b inserted in the first jack, the circuits would pass through the wage register Bw and the time registers B and Bt. The circuits through these registers may be readily traced thus: from the sleeve of plug b into conductor 91, through register Bw, conductor 92', through switch 93, (provided the same is closed, as it would be upon the workman's arrival) thence into conductor 89 to ground 90. From the tip of plug b the current may be traced through conductor 94, through time register Bt, conductor 95, time register B, switch 93 to ground 90. The circuits from ground 76 of the battery to tip and sleeve of the plug b would be the same as those described in connection with plug a. As previously mentioned the series of jacks is divided in the present instance, into three groups of three jacks each, each series representing a certain rate. As shown in the drawings, plug a is inserted in the first group, which means that the wage register controlled by the plug operates at a ten cent rate. Now plug a might be inserted in any jack of the other groups to cause the wage register Aw to operate at a different rate. To illustrate this operation at a different rate I have shown the plug c inserted in the group of jacks which corresponds with the five cent rate. Let us now trace the various circuits with the plug c in the posi-

tion shown in Fig. 1: Starting with ground 76, current will pass through the right half of the battery into conductor 75, thence into conductor 75' to the point 96. At this point the circuit divides, one portion passing into contact 66 over to contact 61, (during the portion of the cycle in which the contact 61 is forced to the right by the deviations in the grooves) thence into conductor 81, conductor 82, sleeve contact 61', conductor 97, wage register Cw, conductor 98, switch 99 (which of course would be closed) thence to the ground 90. The other portion of the circuit that divided at the point 96 is traced as follows: point 96, contacts 72 and 64, (during that portion of the cycle in which the contact 64 is forced against the contact 72) thence into the conductor 77 to the tip contact 78, through the tip of the plug into conductor 100, time register Ct, conductor 101, into the workman's individual time register C, and thence through switch 99 to the ground. During that portion of the cycle in which the spring contacts working in the grooves on the disks are forced to the left, as viewed in Fig. 1, the circuits would be the same except that instead of passing through the right half of the battery, the circuits would be traced from the ground through the left half, as already indicated in connection with certain circuits traced through the plug a. From the circuits that have thus far been traced, it will be noted that plug a controls registers A, At and Aw; plus b controls registers B, Bt, and Bw; and plug c controls registers C, Ct, and Cw. In other words, the particular plug assigned to each workman will control his particular registers.

As may be seen from Fig. 1, any one of the plugs a, b and c may be inserted in any one of the series of jacks so that a register of any workman may be made to operate at any one of the desired rates. Thus if it is desired that the workman whose plug is a shall work at say a fifteen cent rate, all that is necessary is to take plug a and place it in any one of the group of jacks representing that particular rate. In the instance illustrated that group comprises the last three of the series of jacks.

At this time I desire to call attention to the diagrammatic representation of the registers in Fig. 1. It is intended that the circles A, At, etc., together with their corresponding gear connections indicate diagrammatically the register operating devices and their appropriate gearing, as shown in Figs. 2, 3, and 4. The time registers At, Bt and Ct totalize into the summation time register T in order to have an indication of the total amount of time consumed by the workmen, as shown by each workman's individual register. The only difference between the time registers A, B, 130

and C and time registers A_t, B_t and C_t is that the first set of time registers has each register independent of the other, while in the second set of registers the registers are 5 differentially geared together so as to control the actuation of the summation register. The summation wage register W_t is geared to the individual wage registers A_w, B_w and C_w, to indicate the total or sum of their 10 actuations.

The six registers indicated at the right of Fig. 1 are intended to represent jobs. The registers j₁, j₂ and j₃ give indications of what might be distinguished as job J, while 15 the registers j₄, j₅ and j₆ are to indicate another job J'. In the present instance, I have shown but two jobs, although it is apparent that any number of separate jobs might be represented by the necessary registers. Furthermore I have shown three registers for each job. This is simply because, by way of example, I have illustrated but three workmen's registers. Suppose it is desired to put a workman whose plug is a 20 on job J. In that case plug a, being in the position in which it is shown, for the sake of illustration, in Fig. 1, it would be merely necessary to place plug a' in one of the jacks 102, 103, or 104, these jacks controlling 25 respectively the job registers j₁, j₂ and j₃. If, now, plug a' be inserted in the jack 102, the circuit through the job register j₁ would be traced as follows: From conductor 85, the circuit as previously traced in connection with plug a would divide at the point 105, a portion of it passing into the wage register A_w, as previously described, the other portion passing from point 105 into conductor 106, the tip of plug a', tip contact 107, conductor 108, through job register j₁, conductor 109, the sleeve contact 110 of jack 102, through the sleeve of plug a', conductor 111 to switch 88, thence through conductor 89 to the ground 90. Inasmuch as 40 the rate at which the register or registers controlled by the plug a' is primarily determined by the particular jack into which the plug is inserted, it is evident that the particular job register controlled by a plug a' would essentially operate at the same rate as the wage register controlled by the plug a. Inasmuch as it is the plug a that determines the rate of actuation of the corresponding wage register any job register 45 which may be placed in circuit by the plug a' can operate only at the same rate at which the wage register is operating, as determined by the plug a. The job plug b' is associated with the workmen's plug b in the same manner that job plug a' is associated with the plug a, as above described. Similarly the job plug c' is associated with the workmen's plug c.

With plug b inserted in any particular 50 jack in the series, and the job plug b' in-

serted in any particular jack in the job series, the circuit from the sleeve of plug b will divide at the point 112 in the conductor 91, part of it going through the wage register B_w, as before described, and part of it following conductor 113 to the tip of job plug b', from there it will pass into the particular job register and return through the sleeve of the plug b' into conductor 114, thence through the switch 93 to the ground 90. The circuit through the job register j₆ as completed by the job plug c' with the workmen's plug c inserted as shown is traced as follows: At the point 115 in the conductor 97, the circuit from the sleeve of plug c divides, a portion passing through the wage register C_w, as before described, the other portion passing from the point 115 into the conductor 116, to the tip of job plug c' to the tip contact 117, conductor 118, through the job register j₆, conductor 117, sleeve contact 120, through the sleeve of plug c', into conductor 121, thence through the switch 99 to the ground 90. Because of the parallel relation of the circuits through a particular wage register and any job register associated with the workmen's register, by the insertion of a particular job plug, it follows that a wage register may be actuated without the corresponding actuation of any job register, 55 so that a workman's wage register may indicate the accumulation of wages, even though the workman has not been assigned to any job. The fact, of course, that a particular workman has not been assigned to any job may not by any means be his fault, but in case it is desired to have an arrangement whereby there will be no accumulation of wages unless the workman has been assigned to a job, the scheme shown in Fig. 7 60 may be resorted to. This figure shows only those circuits which are different from those indicated in Fig. 1.

In Fig. 7 let A' indicate the workman's individual time register. Let it be assumed that the workman's switch 122 be closed and the plug a'' inserted in jack 123. The circuit would then be traced from the battery as described in connection with Fig. 1 to the sleeve contact 124, thence through the 65 sleeve of the plug a'', into conductor 125, from there into the wage register A_w', through the conductor 126, individual time register A', conductors 127, 128, 129, through the tip of job plug a'. Now unless this job plug is inserted in one of the job jacks, the circuit through the workman's individual time register A' and his wage register A_w' would not be completed, and the wage register will show no accumulation of wages. In 70 order that this wage register may be actuated, it is necessary that the workman be assigned to some particular job. Let it, therefore, be assumed that this is the case and that the job plug a' is inserted in the jack 75 130

130. In this case the circuit would be traced from conductor 129, through the tip of plug a_j , the tip contact 131, conductor 132, through the time register j_t , conductor 133, thence to ground 134, completing the circuit through the battery. The circuit from the tip contact 134 of the jack 123 is as follows: through the tip of plug a'' , conductor 135, through the time register A_t' , conductor 136, switch 122, conductors 137, 138, 139, sleeve of job plug A_j , sleeve contact 140, conductor 141, wage register j_w , thence to the ground 134'. From this tracing of the circuits as arranged in Fig. 7, it will be observed that 10 the workman's wage and time registers are in series with the corresponding wage and time registers of any particular job so that the circuits through these registers cannot be completed unless both the workman's 15 plug and the job plug are inserted in the desired jacks. The modification presented in Fig. 7 shows the flexibility of my system as illustrated in the embodiment of Fig. 1.

Directing attention to Fig. 1, it will be observed that the job registers j_1 , j_2 and j_3 20 serve that the job registers j_1 , j_2 and j_3 totalize into the register J_3 , while the individual job registers j_4 , j_5 and j_6 totalize into the summation register J_6 . These registers J_3 and J_6 totalize into the summation 25 job register J_t . The summation wage register W_t and the summation job register J_t are connected together by the differential gear 142. Now these summation registers are arranged to be actuated in opposite directions so that the register X actuated by the differential gear 142 will indicate the difference 30 between the amount of actuation of register W_t and the amount of actuation of register J_t . Under normal conditions these registers should give corresponding indications 35 so that the central wheel of the differential gear 142 would remain stationary and the register X remain idle. However, if any workman's plug has been inserted and his particular wage register accumulates without 40 his having been assigned to a job, then the wage register W_t would give indications in excess of those given by the job register J_t , which excess would be indicated by the register X . It will thus be seen that this register X gives indications of unassigned jobs.

It is to be understood that, as shown in Fig. 1, the relation of the registers is to each other such that additional registers may be 45 added if desired in any of the series to meet different demands of the system, and that for any operative condition the end gear mounted upon any one of the shafts is to be held against rotation in order that the added 50 movements of the common gears of the differential mechanism may be transmitted from the opposite ends of such shafts to the totalizing registers.

The means which I have provided for de- 55 cumulating the registers, or, in other words,

bringing them back to zero, is indicated to be operated manually, or at least mechanically as distinguished from anything like an electrically controlled operation. On one end of the suitably mounted shaft 143 is the gear 144 which by shifting the shaft may be brought into engagement with the gear 145. When this engagement between the gears 144 and 145 has been effected, the shaft 143 is rotated in a direction to cause actuation 70 of the registers mechanically connected therewith in a direction to decumulate such registers. This rotation of the shaft 143 in the reverse direction may be done manually, in which case I provide a handle 146. 80

In order to prevent decumulation of the registers below the zero or starting point, I have arranged locking means in the shape of a bar 147 as shown in Fig. 3. This bar is pivoted at 148 and is provided with three 85 downwardly extending teeth or projections 149, 150, and 151. With the parts in their positions as shown in Fig. 3, that is to say, in the zero or starting position, the teeth on the bar rest in notches 152, 153 and 154 respectively. The wheels 16 and 18 during the accumulations of the register rotate in the direction indicated by the arrows. It will be observed that the shape of the teeth 149 and 151 is such that upon this rotation 90 of the wheels the teeth will be lifted out of their respective notches, thus causing no interference with the free rotation of the wheels during the normal operation of the register. The projection 150 is provided 95 with no such cam surface as the teeth 149 and 151 are provided with, but the notch or recess 150 in the wheel 17 is made sufficiently large to permit a certain amount of rotation of the wheel 17 before the tooth 150 engages 100 the wall of the recess 153. This play of the tooth 150 in the recess 153 is necessary in order to allow sufficient rotation of the wheel 16 to permit tooth 151 to be forced out of its corresponding notch in the wheel 16. 110 With the bar 147 thus raised, tooth 150 will be out of the recess 153 and wheel 18 will be free to rotate just as the wheels 16 and 17 will be. However, during decumulation of the register, the moment that the parts have 115 reached the position as indicated in Fig. 3, the locking bar 147 will drop into locking position, so that any further rotation of the wheels in a direction opposite to that indicated by the arrows is positively prevented 120 by this bar. In other words, when upon decumulation a register has reached its zero position, the wheels will be locked against further decumulation.

From the description of the embodiment 125 of my invention herein shown, it will be apparent that the arrangement illustrated diagrammatically in Fig. 1 and the modification in Fig. 2 are merely shown by way of examples as describing the principle and es- 130

sence of my invention. Furthermore, although I have shown a specific form of synchronizing mechanism, it is by no means necessary to the purpose of my invention that such particular mechanism be employed. Any suitable form of synchronizing device may be used. Also it will be apparent that certain features of my invention may be used separately from certain other features, as pointed out in the appended claims.

Having thus described my invention, what I claim as new and desire to secure by Letters Patent is:

15. 1. In combination, a source of electric current impulses, a plurality of individual registers each having electromagnetic mechanism adapted to be actuated by said current impulses, means for connecting any of said registers concurrently with said source of current impulses, and means driven by the individual registers for totalizing the actuations of all of the individual registers.
20. 2. In combination, a source of electric current impulses, a plurality of individual registers each adapted to be actuated by said current impulses, means for connecting any of said individual registers with said source of current impulses, a totalizing register, and differential gearing connecting the totalizing register with the individual registers in ratios such that the totalizing register shall be actuated at a rate proportional to the sum of the rates of actuation of all
25. 3. In combination, a source of electric current impulses, a plurality of individual registers each adapted to make a one step advancement upon the passage of a single current impulse therethrough, means for supplying any of said registers concurrently with electric current impulses, a totalizing register, and means driven by the individual registers for actuating the totalizing register by an amount proportional to the sum of the actuations of the individual registers.
30. 4. In combination, a plurality of sources of current impulses of different rates, a plurality of individual registers each adapted to make a one step advancement upon the passage of a single current impulse therethrough, means for connecting any of the individual registers concurrently with any of said sources of current impulses, and means operated by the individual registers for automatically indicating the total of the actuations of all of the individual registers.
35. 5. In combination, a plurality of sources of current impulses of different rates, a plurality of individual registers each adapted to make a one step advancement upon the passage of a single current impulse therethrough, means for connecting any individual register with any of said sources of current impulses, a totalizing register, and dif-

ferential gearing for actuating the totalizing register at a rate proportional to the sum of the rates of actuation of the individual registers.

6. In combination, a totalizing register, a plurality of actuating gears, differential gearing connecting the totalizing register with the actuating gears in ratios such that the actuation of the totalizing register shall be proportional to the sum of the actuations of the actuating gears, a source of electric current impulses, an electromagnetic mechanism associated with each actuating gear for causing the one step advancement of the same upon the passage of a current impulse therethrough, and means for connecting any of the electromagnetic actuating mechanisms with said source of current impulses.

7. In combination, a totalizing register, a plurality of actuating gears, differential gearing connecting the totalizing register with the actuating gears in ratios such that the actuation of the totalizing register shall be proportional to the sum of the actuations of the actuating gears, a plurality of sources of electric current impulses of various rates, an electromagnetic mechanism associated with each actuating gear for causing the one step advancement thereof upon the passage of a single current impulse therethrough, and means for connecting any of said electromagnetic actuating mechanisms with any of said sources of current impulses.

8. In combination, a totalizing register, a plurality of actuating gears therefor, mechanism connecting the actuating gears with the totalizing register in ratios such that the actuation of the totalizing register shall be proportional to the sum of the actuations of the actuating gears, a source of electric current, an electromagnetic mechanism associated with each actuating gear for operating the same, and means for connecting any of said electromagnetic actuating mechanisms concurrently with said sources of current.

9. In combination, a totalizing register, a plurality of actuating gears therefor, mechanism connecting the actuating gears with the totalizing register in ratios such that the actuation of the totalizing register shall be proportional to the sum of the actuations of the actuating gears, a plurality of sources of electric impulses of various frequencies, an electromagnetic step by step actuating mechanism associated with each actuating gear, and means for connecting any of said electromagnetic actuating mechanisms concurrently with any of said sources of current impulses.

10. In combination, a totalizing register, a plurality of actuating gears, differential gearing connecting the totalizing register with said actuating gears in ratios such that the actuation of the totalizing register shall

be proportional to the sum of the actuations of the actuating gears, a source of electric current, an electromagnetic mechanism associated with each actuating gear for operating the same, and means for connecting any of said electromagnetic actuating mechanisms concurrently with said sources of current.

11. In combination, a totalizing register, a plurality of actuating gears, differential gearing connecting the totalizing register with said actuating gears in ratios such that the actuations of the totalizing register shall be proportional to the sum of the actuations of the actuating gears, a plurality of sources of electric impulses of various frequencies, an electromagnetic step by step actuating mechanism associated with each actuating gear, and means for connecting any of said electromagnetic actuating mechanisms concurrently with any of said sources of current impulses.

12. In combination, a source of electric current impulses, a plurality of individual wage registers, a plurality of individual job registers, an electromagnetic actuating mechanism associated with each of said wage and job registers and each adapted to cause the one step advancement of the associated register upon the passage of a current impulse therethrough, means for connecting any of the electromagnetic actuating mechanisms associated with the wage registers in circuit with any of the electromagnetic actuating mechanisms associated with any of the individual job registers, means for connecting any such pair of interconnected electromagnetic actuating mechanisms simultaneously in parallel circuit with said source of current impulses, thereby causing the simultaneous advancement of the connected registers, and means for automatically totalizing the actuations of the individual wage registers.

13. In combination, a source of electric current impulses, a plurality of individual wage registers, a plurality of individual job registers, an electromagnetic actuating mechanism associated with each of said wage and job registers and each adapted to cause the one step advancement of the associated register upon the passage of a current impulse therethrough, means for connecting any of the electromagnetic actuating mechanisms associated with the wage registers in circuit with any of the electromagnetic actuating mechanisms associated with any of the individual job registers, means for closing parallel circuits for said current impulses through any such pairs of interconnected electromagnetic actuating mechanisms, and means for automatically totalizing the actuations of the individual job registers.

14. In combination, a plurality of sources

of electric current impulses of different frequencies, a plurality of individual wage registers, a plurality of individual job registers, an electromagnetic actuating mechanism associated with each wage register and with each job register, the said electromagnetic actuating mechanisms each being adapted to cause the one step advancement of the associated register upon the passage of a current impulse therethrough, means for connecting the electromagnetic actuating mechanism associated with any wage register in circuit with the electromagnetic actuating mechanism associated with any job register, means for connecting any such pair of interconnected electromagnetic actuating mechanisms with any of said sources of current impulses, a totalizing register, and differential gearing connecting the totalizing register with the individual registers of one class in gear ratios such that the totalizing register shall be actuated by an amount proportional to the sum of the actuations of the individual registers of that class.

15. In combination, a plurality of sources of electric current impulses of different frequencies, a plurality of individual wage registers, a plurality of individual job registers, an electromagnetic actuating mechanism associated with each wage register and with each job register, the said electromagnetic actuating mechanisms each being adapted to cause the one step advancement of the associated register upon the passage of a current impulse therethrough, means for connecting the electromagnetic actuating mechanism associated with any wage register in circuit with the electromagnetic actuating mechanism associated with any job register, means for connecting any such pair of interconnected electromagnetic actuating mechanisms with any of said sources of current impulses, a wage totalizing register, differential gearing connecting the wage totalizing register with the individual wage registers in gear ratios such that the actuations of the wage totalizing register shall be proportional to the sum of the actuations of the individual wage registers, a job totalizing register, and differential gearing connecting the job totalizing register with the individual job registers in gear ratios such that the actuation of the job totalizing register shall be proportional to the sum of the actuations of the individual job registers.

16. In combination, a source of electric current impulses, a plurality of individual wage registers, a plurality of individual job registers, an electromagnetic actuating mechanism associated with each of said wage and job registers each adapted to cause the one step advancement of the associated register upon the passage of a current impulse therethrough, means for connecting any of the

- electromagnetic actuating mechanisms associated with the wage registers in circuit with any of the electromagnetic actuating mechanisms associated with the individual job registers, means for connecting any such pair of interconnected electromagnetic actuating mechanisms with said source of current impulses, a totalizing register, and differential gearing connecting the totalizing register with the individual registers of one class in gear ratios such that the totalizing register shall be actuated by an amount proportional to the sum of the actuations of the individual registers of that class. 10
- 15 17. In combination, a source of electric current impulses, a plurality of individual wage registers, a plurality of individual job registers, an electromagnetic actuating mechanism associated with each of said wage and job registers each adapted to cause the one step advancement of the associated register upon the passage of a current impulse therethrough, means for connecting any of the electromagnetic actuating mechanisms associated with the wage registers in circuit with any of the electromagnetic actuating mechanisms associated with the individual job registers, means for connecting any such pair of interconnected electromagnetic actuating mechanisms with said source of current impulses, a wage totalizing register, differential gearing connecting the wage totalizing register with the individual wage registers in gear ratios such that the actuation of the wage totalizing register shall be proportional to the sum of the actuations of the individual wage registers, a job totalizing register, and differential gearing connecting the job totalizing register with the individual job registers in gear ratios such that the actuation of the job totalizing register shall be proportional to the sum of the actuations of the individual job registers. 25
- 30 18. In combination, a source of electric current, a plurality of individual wage registers, a plurality of individual job registers, an electromagnetic actuating mechanism associated with each of said wage and job registers, means for connecting the electromagnetic actuating mechanism associated with any wage register in circuit with the electromagnetic actuating mechanism associated with any job register, and means for connecting any such pairs of interconnected electromagnetic actuating mechanisms concurrently in circuit with said source of current. 35
- 35 19. In combination, a source of electric current, a plurality of individual wage registers, a plurality of individual job registers, an electromagnetic actuating mechanism associated with each of said wage and job registers, means for connecting the electromagnetic actuating mechanism associated with any wage register in circuit with the electromagnetic actuating mechanism associated with any job register, means for connecting any such pairs of interconnected electromagnetic actuating mechanisms concurrently in circuit with said source of current, and means for automatically totalizing the actuations of the individual registers of one of said classes. 40
- 40 20. In combination, a source of electric current, a plurality of individual wage registers, a plurality of individual job registers, an electromagnetic actuating mechanism associated with each of said wage and job registers, means for connecting the electromagnetic actuating mechanism associated with any wage register in circuit with the electromagnetic actuating mechanism associated with any job register, means for connecting any such pairs of interconnected electromagnetic actuating mechanisms concurrently in circuit with said source of current, a totalizing register, and differential gearing connecting said totalizing register with the individual registers of one class in gear ratios such that the totalizing register shall be actuated by an amount proportional to the sum of the actuations of the individual registers of that class. 45
- 45 21. In combination, a source of electric current, a plurality of individual wage registers, a job register, a plurality of actuating gears for the job register, differential gearing connecting the job register with said actuating gears in ratios such that the actuations of the job register shall be proportional to the sum of the actuations of the actuating gears, an electromagnetic actuating mechanism associated with each individual register and with each of said actuating gears, means for connecting the electromagnetic actuating mechanism associated with any individual wage register in circuit with the electromagnetic actuating mechanism associated with any of said actuating gears, and means for connecting any such pair of interconnected electromagnetic actuating mechanisms with said source of current. 50
- 50 22. In combination, a plurality of sources of electrical impulses of different frequencies, a plurality of switch terminals connected with each source, a plurality of job registers, a plurality of electromagnetic actuating mechanisms associated with each of said job registers and each adapted to cause the one step advancement of such register upon the passage of a current impulse therethrough, a switch terminal for each of said electromagnetic actuating mechanisms, and a plurality of link conductors each adapted to close circuit from a switch terminal for any of said sources of current through a switch terminal for any of said electromagnetic actuating mechanisms. 55
- 55 23. In combination, a plurality of sources of electrical impulses of different frequencies, a plurality of switch terminals connected with each source, a plurality of job registers, a plurality of electromagnetic actuating mechanisms associated with each of said job registers and each adapted to cause the one step advancement of such register upon the passage of a current impulse therethrough, a switch terminal for each of said electromagnetic actuating mechanisms, and a plurality of link conductors each adapted to close circuit from a switch terminal for any of said sources of current through a switch terminal for any of said electromagnetic actuating mechanisms. 60

- of electrical impulses of different frequencies, a plurality of switch terminals connected with each source, a plurality of job registers, a plurality of electromagnetic actuating mechanisms associated with each of said job registers and each adapted to cause the one step advancement of such register upon the passage of a current impulse therethrough, a switch terminal for each of said electromagnetic actuating mechanisms, a plurality of link conductors each adapted to close circuit from a switch terminal for any of said sources of current through a switch terminal for any of said electromagnetic actuating mechanisms, a plurality of wage registers, an electromagnetic actuating mechanism for each wage register adapted to cause the one step advancement of the associated wage register upon the passage of a current impulse therethrough, one of the electromagnetic mechanisms for actuating a wage register being included in the circuit of each of said link conductors.
24. In combination, a plurality of sources of electrical current impulses of different frequencies, a plurality of switch terminals connected with each source, a plurality of job registers, a plurality of actuating gears for each job register, differential gearing connecting each job register with its actuating gears in ratios such that the actuation of each job register shall be proportional to the sum of the actuations of the associated actuating gears, an electromagnetic actuating mechanism associated with each of said actuating gears and adapted to cause the one step advancement of the associated actuating gear upon the passage of a current impulse therethrough, a switch terminal for each of said electromagnetic actuating mechanisms, and a plurality of link conductors each adapted to close circuit from a switch terminal for any of said sources of current through a switch terminal for any of said electromagnetic actuating mechanisms.
25. In combination, a plurality of sources of electrical current impulses of different frequencies, a plurality of switch terminals connected with each source, a job register, a plurality of actuating devices therefor, mechanism connecting the job register with the actuating devices in ratios such that the actuation of the register shall be proportional to the sum of the actuations of the individual actuating devices, an electromagnetic actuating mechanism associated with each actuating device to cause the one step advancement of the actuating device upon the passage of a current impulse therethrough, a switch terminal for each of said electromagnetic actuating mechanisms, and a plurality of link conductors each adapted to close circuit from a switch terminal for any of said sources of current through a switch terminal for any of said electromagnetic actuating mechanisms, a plurality of wage registers, and electromagnetic actuating mechanism associated with each wage register and adapted to cause the one step advancement of the associated wage register upon the passage of a current impulse therethrough, one electromagnetic mechanism for actuating a wage register being included in the circuit of each of said link conductors.
26. In combination, a plurality of sources of electrical current impulses of different frequencies, a plurality of switch terminals connected with each source, a plurality of job registers, a plurality of actuating gears for each job register, differential gearing connecting each job register with its actuating gears in ratios such that the actuation of each job register shall be proportional to the sum of the actuations of the associated actuating gears, an electromagnetic actuating mechanism associated with each of said actuating gears and adapted to cause the one step advancement of the associated actuating gear upon the passage of a current impulse therethrough, a switch terminal for each of said electromagnetic actuating mechanisms, a plurality of link conductors each adapted to close circuit from a switch terminal for any of said sources of current through a switch terminal for any of said electromagnetic actuating mechanisms, a plurality of wage registers, and electromagnetic actuating mechanism associated with each wage register and adapted to cause the one step advancement of the associated wage register upon the passage of a current impulse therethrough, one electromagnetic mechanism for actuating a wage register being included in the circuit of each of said link conductors.
27. In combination, a plurality of sources of electrical current impulses of different frequencies, a plurality of switch terminals connected with each source, a job register, a plurality of actuating devices therefor, mechanism connecting the job register with the actuating devices in ratios such that the actuation of the register shall be proportional to the sum of the actuations of the individual actuating devices, an electromagnetic actuating mechanism associated with each actuating device to cause the one step advancement of the actuating device upon the passage of a current impulse therethrough, a switch terminal for each of said electromagnetic actuating mechanisms, a plurality of link conductors each adapted to close circuit from a switch terminal for any of said sources of current through a switch terminal for any of said electromagnetic actuating mechanisms, a plurality of wage registers, and electromagnetic actuating mechanism associated with each wage register and adapted to cause the one step advancement of the associated wage register upon the passage of a current impulse therethrough, one electromagnetic mechanism for actuating a wage register being included in the circuit of each of said link conductors.
28. In combination, a plurality of sources

- of electrical impulses of different frequencies, a plurality of switch terminals connected with each source, a plurality of job registers, a plurality of electromagnetic actuating mechanisms associated with each of said job registers and each adapted to cause the one step advancement of such register upon the passage of a current impulse therethrough, a switch terminal for each of said electromagnetic actuating mechanisms, a plurality of link conductors each adapted to close circuit from a switch terminal for any of said sources of current through a switch terminal for any of said electromagnetic actuating mechanisms, a plurality of wage registers, an electromagnetic actuating mechanism for each wage register adapted to cause the one step advancement of the associated wage register upon the passage of a current impulse therethrough, one of the electromagnetic mechanisms for actuating a wage register being included in the circuit of each of said link conductors, a totalizing register for each of said classes of registers, and differential gearing associated with each totalizing register and connected with the individual registers of the class to which such totalizing register is assigned, the ratio of gearing being such as to cause the actuation of the totalizing register at a rate proportional to the sum of the rates of actuation of the individual registers of that class.

31. In combination, a plurality of sources of electrical current impulses of different frequencies, a plurality of switch terminals connected with each source, a plurality of job registers, a plurality of actuating gears for each job register, differential gearing connecting each job register with its actuating gears in ratios such that the actuation of each job register shall be proportional to the sum of the actuations of the associated actuating gears, an electromagnetic actuating mechanism associated with each of said actuating gears and adapted to cause the one step advancement of the associated actuating gear upon the passage of a current impulse therethrough, a switch terminal for each of said electromagnetic actuating mechanisms, a plurality of link conductors each adapted to close circuit from a switch terminal for any of said sources of current through a switch terminal for any of said electromagnetic actuating mechanisms, a totalizing register for each of said classes of registers, and differential gearing associated with each totalizing register and connected with the individual registers of the class to which such totalizing register is assigned, the ratio of gearing being such as to cause the actuation of the totalizing register at a rate proportional to the sum of the rates of actuation of the individual registers of that class.

32. In combination, a plurality of sources of electrical impulses of different but constant frequencies, a plurality of telephone spring jacks connected with each source of current impulses, a plurality of job registers, a plurality of actuating gears for each register, differential gearing connecting each job register with its actuating gears in ratios such that the actuation of each job register shall be proportional to the sum of the rates of actuation of the individual registers of that class.

- actuations of its actuating gears, an electromagnetic actuating mechanism associated with each of said actuating gears and adapted to cause the one step advancement of the 5 associated actuating gear upon the passage of a current impulse therethrough, a spring jack connected with each of said electromagnetic actuating mechanisms, a plurality of link conductors each terminating in telephone plugs adapted for insertion in the 10 spring jacks, the insertion of the plugs of any link conductor respectively in a spring jack connected with a source of current impulses and a spring jack connected with one 15 of said electromagnetic actuating mechanisms serving to close circuit from that source of current impulses through that electromagnetic actuating mechanism, a plurality of individual wage registers, an electromagnetic actuating mechanism associated with each wage register and adapted to cause the one step advancement of the associated wage register upon the passage of a current 20 impulse therethrough, one of the electromagnetic mechanisms for actuating a wage register being included in the circuit of each of said link conductors, a wage totalizing register, and differential gearing connecting the wage totalizing register with the individual 25 wage registers in gear ratios such that the actuation of the wage totalizing register shall be proportional to the sum of the actuations of the individual wage registers.
33. In combination, a register, a system 30 of differential gearing whose common gear is connected with the register, an electromagnetic ratchet mechanism associated with each of the driving gears of the differential system, each electromagnetic mechanism being adapted to cause the one step advancement 35 of the register upon the passage of a current impulse therethrough, a plurality of sources of electrical impulses of different frequencies, and means for connecting any 40 of said electromagnetic actuating mechanisms with any of said sources of current impulses.
34. In combination, a register, a system 45 of differential gearing whose common gear is connected with the register, an electromagnetic ratchet mechanism associated with each of the driving gears of the differential system, each electromagnetic mechanism being adapted to cause the one step advancement 50 of the register upon the passage of a current impulse therethrough, a source of electrical impulses, and means for connecting any of said electromagnetic actuating mechanisms with said source of current impulses.
35. In combination, a register, a system 55 of differential gearing whose common gear is connected with said register, an electromagnetic actuating mechanism associated with each driving gear of the differential system,
- a source of electrical current for actuating any of the electromagnetic actuating mechanisms connected therewith, and means for connecting any of said electromagnetic actuating mechanisms with said source of current 70.
36. In a device of the class described, the combination of a plurality of concentrically grouped differential gears each comprising a common gear and two driven gears, the 75 driven gear at one end of the group being fixed to prevent rotation, a register connected with the driven gear at the other end of the group, means connecting together the adjacent driven gears of all of the differential gears of the group, and electromagnetic ratchet mechanisms for actuating any of the common gears.
37. In a device of the class described, the combination of a plurality of concentrically 80 grouped differential gears each comprising a common gear and two driven gears, the driven gear at one end of the group being fixed to prevent rotation, a register connected with the driven gear at the other end of the group, means connecting together the adjacent driven gears of all of the differential gears of the group, and means for driving each of the common gears.
38. In a device of the class described, the 85 combination of a plurality of concentrically grouped differential gears each comprising a common gear and two driven gears, the driven gear at one end of the group being fixed to prevent rotation, a register connected with the driven gear at the other end of the group, means connecting together the adjacent driven gears of all of the differential gears of the group, and means for connecting any of the common gears, to be driven 90 by said clock-controlled driving mechanism.
39. In a device of the class described, the combination of a plurality of concentrically 95 grouped differential gears each comprising a common gear and two driven gears, a register connected with one of the driven gears, means connecting together the adjacent driven gears of all of the differential gears of the group, and means for actuating alternate common gears in one direction and the other common gears in reverse direction.
40. In a device of the class described, the combination of a plurality of concentrically 100 grouped differential gears each comprising a common gear and two driven gears, the driven gear at one end of the group being fixed to prevent rotation, a register connected with the driven gear at the other end of the group, means connecting together the adjacent driven gears of all of the differential gears of the group, and electromagnetic 105 ratchet mechanism connected with each of the common gears, sources of electrical cur- 110

rent impulses of various rates, and means for connecting any of the electromagnetic ratchet mechanisms with any of said sources of current impulses.

- 5 41. In a device of the class described, the combination of a plurality of concentrically grouped differential gears each comprising a common gear and two driven gears, a register connected with one of the driven gears, means connecting together the adjacent driven gears of all of the differential gears of the group, and means for actuating the various common gears at different rates for any desired periods of time.
- 10 42. In combination, a plurality of individual registers provided each with electro-magnetic means for actuating the same, a source of electric impulses for periodically energizing said electro-magnetic means to operate the registers at a rate determined by the frequency of the impulses, and a summation-register geared to said individual registers to indicate the total of the actuations of said individual registers.
- 15 43. In combination, a plurality of individual registers provided each with electro-magnetic means for actuating the same, a source of electric impulses of predetermined frequency, means for establishing readily separable circuit-connections between said source and any register or registers to operate the same at a rate dependent upon said frequency, and a summation-register geared to said individual registers to indicate the total of the actuations of said individual registers.
- 20 44. In combination, a plurality of individual registers provided each with electro-magnetic means for actuating the same, a source of electric impulses of predetermined frequency, a series of switch-terminals connected with said source, a cooperating contact-terminal connected with each register for establishing readily separable circuit-connections between said source and any register or registers to operate the same at a rate dependent upon said frequency, and a summation-register geared to said individual registers to indicate the total of the actuations of said individual registers.
- 25 45. In combination, a plurality of individual registers provided each with electro-magnetic means for actuating the same, means for generating electric impulses of different frequencies, readily controlled circuit-connections between said generating means and said individual registers for selectively determining the rate of actuation of any register, and a summation-register differentially geared to said individual registers to indicate the total of the actuations of said individual registers.
- 30 46. In combination, a plurality of individual registers provided each with electro-magnetic means for actuating the same,

means for generating electric impulses of different predetermined frequencies, sets of switch-terminals having connections with said generating means such that each set of terminals controls the impulses of a certain frequency, independently of any other set, a contact-terminal connected with each register adapted to cooperate with any switch-terminal for selectively establishing circuit-connections between said generating means and any one or more registers to actuate the same at a rate dependent upon the particular switch-terminal with which any one register has connection, and a summation-register differentially geared to said individual registers to indicate the total of the actuations of said individual registers.

47. In combination, a source of electric current, a plurality of time-controlled interrupting devices in circuit therewith for sending current-impulses through the circuits at different predetermined frequencies, a set of switch-terminals connected with each interrupting device whereby each set of terminals controls the impulses of a certain frequency, a plurality of individual registers having each electro-magnetic actuating means adapted to be energized by said current-impulses, a contact-terminal connected with each register adapted to cooperate with any switch-terminal for selectively establishing circuit-connections between said source and any one or more registers to actuate the same at a rate dependent upon the particular switch-terminal with which any one register has connection, and a summation-register differentially geared to said individual registers to indicate the total actuation of said individual registers.

48. In combination, a source of electric impulses of predetermined frequency, a plurality of wage-registers, a plurality of corresponding job-registers, electro-magnetic means associated with each register for actuating the same at a rate dependent upon the said frequency, and circuit-connections between said source of impulses and said registers for connecting the wage-registers or any number thereof in parallel with their respective job-registers whereby any job-register may be cut out of circuit without affecting the actuation of the corresponding wage-register.

49. In combination, a source of electric impulses of predetermined frequency, a plurality of individual wage-registers, a plurality of corresponding individual job-registers, electro-magnetic means associated with each register for actuating the same at a rate dependent upon the said frequency, circuit-connections between said source of impulses and said registers for connecting the wage-registers or any number thereof in parallel with their respective job-registers whereby any job-register may be cut out of circuit

- without affecting the actuation of the corresponding wage-register, a summation wage-register controlled by said individual wage-registers to indicate the total of the actuations of the individual wage-registers, and a summation job-register controlled by said individual job-registers to indicate the total of the actuations of the individual job-registers.
5. 50. In combination, a source of electric impulses of predetermined frequency, a plurality of individual wage-registers, a plurality of corresponding individual job-registers, electro-magnetic means associated with each register for actuating the same at a rate dependent upon the said frequency, circuit-connections between said source of impulses and said register for connecting the wage-registers or any number thereof in parallel with their respective job-registers whereby any job-register may be cut out of circuit without affecting the actuation of the corresponding wage-register, a summation wage-register differentially geared to said individual wage-registers to indicate the total of the actuations of the individual wage-registers, and a summation job-register differentially geared to said individual job-registers to indicate the total of the actuations of the individual job-registers.
10. 51. In combination, a source of electric impulses of predetermined frequency, a plurality of individual wage-registers, a plurality of corresponding individual job-registers, electro-magnetic means associated with each register for actuating the same at a rate dependent upon the said frequency, circuit-connections between said source of impulses and said registers for connecting the wage-registers or any number thereof in parallel with their respective job-registers whereby any job-register may be cut out of circuit without affecting the actuation of the corresponding wage-register, a summation wage-register differentially geared to said individual wage-registers to indicate the total of the actuations of the individual wage-registers, a summation job-register differentially geared to said individual job-registers to indicate the total of the actuations of the individual job-registers, and a differential register geared to said summation-registers to indicate the difference between the amount of actuation of one summation-register and the amount of actuation of the other summation-register.
15. 52. In combination, a source of electric impulses of predetermined frequency, a plurality of wage-registers, a plurality of corresponding job-registers, electro-magnetic means associated with each register for actuating the same at a rate dependent upon the said frequency, and circuit-connections between said source of impulses and said registers for connecting the wage-registers or any
- number thereof in parallel with their respective job-registers, the point of connection being such that any job-register may be cut out of circuit without affecting the actuation of the corresponding wage-register, but that no job-register may be cut into the actuating circuit when the corresponding wage-register is out of circuit.
20. 53. In combination, means for generating electric impulses of different predetermined frequencies, a plurality of wage-registers, a plurality of job-registers, electro-magnetic actuating means associated with each register, sets of switch-terminals having connections with said generating means such that each set of terminals controls the impulses of a certain frequency independently of any other set, and a contact-terminal connected with each register adapted to coöperate with any switch-terminal for selectively establishing circuit-connections between said generating means and any one or more registers to actuate the same at a rate dependent upon the particular switch terminal with which any one register has connection, said circuit-connections being such that any job-register may be cut out of circuit without affecting the corresponding wage-register.
25. 54. In combination, means for generating electric impulses of different predetermined frequencies, a plurality of individual wage-registers, a plurality of individual job-registers, electro-magnetic actuating means associated with each register, sets of switch-terminals having connections with said generating means such that each set of terminals controls the impulses of a certain frequency independent of any other set, a contact-terminal connected with each register adapted to coöperate with any switch-terminal for selectively establishing circuit-connections between said generating means and any one or more registers to actuate the same at a rate dependent upon the particular switch-terminal with which any one register has connection, said circuit-connections being such that any job-register may be cut out of circuit without affecting the actuation of the corresponding wage-register, a summation wage-register controlled by said individual wage-registers to indicate the total of the actuations of the individual wage-registers, and a summation job-register controlled by said individual job-registers to indicate the total of the actuations of the individual job-registers.
30. 55. In combination, means for generating electric impulses of different predetermined frequencies, a plurality of individual wage-registers, a plurality of individual job-registers, electro-magnetic means associated with each register, sets of switch-terminals having connections with said generating means such that each set of terminals controls the impulses of a certain frequency in-

- dependent of any other set, a contact-terminal connected with each register adapted to coöperate with any switch-terminal for selectively establishing circuit-connections between said generating means and any one or more registers to actuate the same at a rate dependent upon the particular switch-terminal with which any one register has connection, said circuit-connections being such that any job-register may be cut out of circuit without affecting the actuation of the corresponding wage-register, a summation wage-register differentially geared to said individual wage-registers to indicate the total of the actuations of the individual wage-registers, and a summation job-register differentially geared to said individual job-registers to indicate the total of the actuations of the individual job-registers.
56. In combination, means for generating electric impulses of different predetermined frequencies, a plurality of individual wage-registers, a plurality of individual job-registers, electro-magnetic actuating means associated with each register, sets of switch-terminals having connections with said generating means such that each set of terminals controls the impulses of a certain frequency independent of any other set, a contact-terminal connected with each register adapted to coöperate with any switch-terminal for selectively establishing circuit-connections between said generating means and any one or more registers to actuate the same at a rate dependent upon the particular switch-terminal with which any one register has connection, said circuit-connections being such that any job-register may be cut out of circuit without affecting the actuation of the corresponding wage-register, a summation wage-register differentially geared to said individual wage-registers to indicate the total of the actuations of the individual wage-registers, a summation job-register differentially geared to said individual job-registers to indicate the total of the actuations of the individual job-registers, and a differential register geared to said summation-registers to indicate the difference between the amount of actuation of one summation-register and the amount of actuation of the other summation-register.
57. In combination, means for generating electric impulses of different predetermined frequencies, a plurality of wage-registers, a plurality of job-registers, electro-magnetic actuating means associated with each register, sets of switch-terminals having connections with said generating means such that each set of terminals controls the impulses of a certain frequency independently of any other set, and a contact-terminal connected with each register adapted to coöperate with any switch-terminal to selectively establish circuit-connections between said generating means and any one or more registers to actuate the same at a rate dependent upon the particular switch-terminal with which the register has connection, said circuit connections being such that any job-register may be cut out of circuit without affecting the actuation of the corresponding wage-register, but that no job-register may be cut into the actuation circuit when the corresponding wage-register is out of circuit.
58. In combination, a source of electric impulses of predetermined frequency, a plurality of wage-registers, a plurality of corresponding time-registers, electro-magnetic means associated with each register for actuating the same at a rate dependent upon the said frequency, circuit-connections between said source of impulses and said registers for cutting said registers or any number thereof into or out of the energizing circuit, and an interconnection between the circuit of every wage-register and the circuit of the corresponding time-register to compel simultaneous control of said circuits.
59. In combination, a source of electric impulses of predetermined frequency, a plurality of wage-registers, a plurality of corresponding job-registers, a plurality of corresponding time-registers, electro-magnetic means associated with each register for actuating the same at a rate dependent upon the said frequency, circuit-connections between said source of impulses and said registers, for cutting said registers or any number thereof into or out of the energizing circuit, an interconnection between the circuit of every wage-register and the circuit of the corresponding job-register whereby any job-register may be cut out of circuit without affecting the actuation of the corresponding wage-register, and an interconnection between the circuit of every wage-register and the circuit of the corresponding time-register to compel simultaneous control of said circuits.
60. In combination, a source of electric impulses of predetermined frequency, a plurality of wage-registers, a plurality of corresponding job-registers, a plurality of corresponding time-registers, electro-magnetic means associated with each register for actuating the same at a rate dependent upon the said frequency, circuit-connections between said source of impulses and said registers, for cutting said registers or any number thereof into or out of the energizing circuit, an interconnection between the circuit of every wage-register and the circuit of the corresponding job-register, such that any job-register may be cut out of circuit without affecting the actuation of the corresponding wage-register, but that no job register may be cut into the actuating circuit when the corresponding wage-register is out of circuit, and an interconnection between

- the circuit of every wage-register and the circuit of the corresponding time-register to compel simultaneous control of said circuits.
61. In combination, means for generating electric impulses of different predetermined frequencies, a plurality of wage-registers, a plurality of corresponding job-registers, a plurality of corresponding time-registers, electro-magnetic means associated with each register for actuating the same at a rate dependent upon the frequency of the energizing impulses, sets of switch-terminals having connections with said generating means such that each set of terminals controls the impulses of a certain frequency independently of any other set, a contact-terminal connected with each register adapted to cooperate with any switch-terminal for selectively establishing circuit-connections between said generating means and any one or more registers to actuate the same at a rate dependent upon the particular switch-terminal with which the register has connection, said circuit connections being such that any job-register may be cut out of circuit without affecting the actuation of the corresponding wage-register, and circuit-connections between said generating means and said time-registers for actuating any one or more of said time-registers at the same predetermined rate irrespective of the rates of actuation of the corresponding wage-registers.
62. In combination, means for generating electric impulses of different predetermined frequencies, a plurality of wage-registers, a plurality of corresponding job-registers, a plurality of corresponding time-registers, electro-magnetic means associated with each register for actuating the same at a rate dependent upon the frequency of the energizing impulses, sets of switch-terminals having connections with said generating means such that each set of terminals controls the impulses of a certain frequency independently of any other set, a contact-terminal connected with each register adapted to cooperate with any switch-terminal for selectively establishing circuit-connections between said generating means and any one or more registers to actuate the same at a rate dependent upon the particular switch-terminal with which the register has connection, circuit-connections between said generating means and said time-registers for actuating any one or more of said time-registers at the same predetermined rate irrespective of the rates of actuation of the corresponding wage-registers, an interconnection between the circuit of every wage-register and the circuit of the corresponding job-register such that any job-register may be cut out of circuit without affecting the actuation of the corresponding wage-register, but that no job-register may be cut into the actuating circuit when the corresponding wage-register is out of circuit, and an interconnection between the circuit of every wage-register and the circuit of the corresponding time-register to compel simultaneous control of said circuits.
63. In combination, means for generating electric impulses of different predetermined frequencies, a plurality of wage-registers, a plurality of corresponding job-registers, a plurality of corresponding time-registers, electro-magnetic means associated with each register for actuating the same at a rate dependent upon the frequency of the energizing impulses, sets of switch-terminals having connections with said generating means such that each set of terminals controls the impulses of a certain frequency independently of any other set, a contact-terminal connected with each register adapted to cooperate with any switch-terminal for selectively establishing circuit-connections between said generating means and any one or more registers to actuate the same at a rate dependent upon the particular switch-terminal with which the register has connection, circuit-connections between said generating means and said time-registers for actuating any one or more of said time-registers at the same predetermined rate irrespective of the rates of actuation of the corresponding wage-registers, an interconnection between the circuit of every wage-register and the circuit of the corresponding job-register such that any job-register may be cut out of circuit without affecting the actuation of the corresponding wage-register, but that no job-register may be cut into the actuating circuit when the corresponding wage-register is out of circuit, and an interconnection between the circuit of every wage-register and the circuit of the corresponding time-register to compel simultaneous control of said circuits.
64. In combination, means for generating electric impulses of different predetermined frequencies, a plurality of wage-registers, a plurality of corresponding job-registers, a plurality of corresponding time-registers, electro-magnetic means associated with each register for actuating the same at a rate dependent upon the frequency of the energizing impulses, sets of switch-terminals having connections with said generating means such that each set of terminals controls the impulses of a certain frequency independently of any other set, a contact-terminal connected with each register adapted to cooperate with any switch-terminal for selectively establishing circuit-connections between said generating means and any one or more registers to actuate the same at a rate dependent upon the particular switch-terminal with which the register has connection, said circuit-connections compelling the simultaneous actuation of any wage-register and its corresponding job-register, and circuit-connections between said generating

means and said time-registers for actuating any one or more of said time-registers at the same predetermined rate irrespective of the rates of actuation of the corresponding wage-registers.

65. In combination, means for generating electric impulses of different predetermined frequencies, a plurality of wage-registers, a plurality of corresponding job-registers, a plurality of corresponding time-registers, electro-magnetic means associated with each register for actuating the same at a rate dependent upon the frequency of the energizing impulses, sets of switch-terminals having connection with said generating means such that each set of terminals controls the impulses of a certain frequency independently of any other set, a contact-terminal connected with each register adapted to coöperate with any switch-terminal for selectively establishing circuit-connections between said generating means and any one or more registers to actuate the same at a rate dependent upon the particular switch-terminal with which the register has connection, said circuit-connections compelling the simultaneous actuation of any wage-register and its corresponding job-register, circuit-connections between said generating means and said time-registers for actuating any one or more of said time-registers at the same predetermined rate irrespective of the rates of actuation of the corresponding wage-registers, and an interconnection between the circuit of every wage-register and the circuit of the corresponding time-register to compel simultaneous control of said circuits.

66. In combination, a series of ratchet wheels, differential gear-mechanism for each ratchet wheel comprising a central gear with which the associated ratchet wheel is operatively connected, a pinion rotatably mounted upon said central gear, a pair of driving gears upon either side of the central gear and in engagement with said pinion, means for operatively connecting together the adjacent driving gears of the successive gear-mechanism, the first of the driving gears in the series being held stationary, an actuating pawl for each ratchet wheel, electro-magnetic means for intermittently actuating the pawls to cause a step-by-step movement of the ratchet wheels alternately in opposite directions whereby the rate of actuation of the last driving gear represents the sum of the rates of actuation of the other driving gears.

67. In combination, a series of ratchet wheels, differential gear-mechanism for each pair of ratchet wheels, a shaft upon which the gear-mechanisms are loosely mounted, each gear-mechanism comprising a central gear with which the associated ratchet wheel is operatively connected, a pinion rotatably mounted upon said central gear, a pair of

driving gears upon either side of the central gear and in engagement with said pinion, sleeves on said shaft for rigidly connecting together the adjacent driving gears of the successive gear-mechanisms, the first of the driving gears in the series being held stationary, an actuating pawl for each ratchet wheel, electro-magnetic means for intermittently actuating the pawls to cause a step-by-step movement of the ratchet wheels alternately in opposite directions whereby the rate of actuation of the last driving gear represents the sum of the rates of actuation of the other driving gears.

68. In combination, a shaft, a series of ratchet wheels loosely arranged thereon, a differential gear-mechanism for each pair of ratchet wheels loosely mounted on said shaft, each gear-mechanism comprising a central gear secured to one of the associated ratchet wheels to rotate therewith, a pinion rotatably mounted upon said central gear, a pair of driving gears upon either side of the central gear and in engagement with said pinion, sleeves on said shaft for rigidly connecting together the adjacent driving gears of the successive gear mechanisms, the first of the driving gears in the series being held stationary, an actuating pawl for each ratchet wheel, electro-magnetic means for intermittently actuating the pawls to cause a step-by-step movement of the ratchet wheels alternately in opposite directions, whereby the rate of actuation of the last driving gear represents the sum of the rates of actuation of the other driving gears.

69. In combination, a plurality of individual registers provided each with electro-magnetic means for actuating the same, a source of electric impulses for periodically energizing said electro-magnetic means to operate the registers at a rate determined by the frequency of the impulses, a summation-register geared to said individual registers to indicate the total of the actuations of said individual registers, and a mechanical locking device associated with each register for securing the same against movement beyond zero-position during decompilation.

70. In combination, a plurality of registers provided each with electro-magnetic means for actuating the same, a source of electric impulses of predetermined frequency, a series of switch-terminals connected with said source, a coöperating contact terminal connected with each register for establishing readily separable circuit-connections between said source and any register or registers to operate the same at a rate dependent upon said frequency, and a mechanical locking device associated with each register for securing the same against movement beyond zero-position during decompilation.

71. In combination, a plurality of regis-

- ters provided each with electro-magnetic means for actuating same, means for generating electric impulses of different predetermined frequencies, sets of switch-terminals having connections with said generating means such that each set of terminals controls the impulses of a certain frequency independently of any other set, a contact-terminal connected with each register adapted to coöperate with any switch-terminal for selectively establishing circuit-connections between said generating means and any one or more registers to actuate the same at a rate dependent upon the particular switch-terminal with which any one register has connection, and a mechanical locking device associated with each register for securing the same against movement beyond zero-position during decumulation.
72. In combination, a plurality of wage registers, a plurality of job registers, electro-magnetic mechanisms for actuating the wage and job registers, a register for indicating the difference between the total actuations of the job registers and the total actuations of the wage registers, a common gear on a differential gear for driving said differential register, and means for actuating the driving gears of said differential gear respectively in proportion to the total actuations of the job and wage registers.
73. In combination, a plurality of wage registers, a plurality of job registers, electro-magnetic mechanisms for actuating the wage and job registers, a register for indicating the difference between the total actuations of the job registers and the total actuations of the wage registers, a common gear on a differential gear for driving said differential register, and differential gearing connected with the individual registers.
74. In an accounting system, actuating means for a waste-wage register, actuating means for a job-register, a source of electric current adapted to energize said actuating means at a predetermined rate, means for connecting said actuating means with said source of current, and means for automatically stopping the actuating means of said waste-wage register on starting the actuating means of said job-register.
75. In combination, contact mechanism, devices for operating said mechanism proportionally to elapsed time, a motor normally driving said devices faster than the rate corresponding to elapsed time, time-controlled mechanism, and mechanism actuated by the motor and time-controlled mechanism for changing the speed of the motor when the contact actuating devices are driven ahead of the time-controlled mechanism.
76. In combination, contact mechanism, a shaft for operating said mechanism, a motor for driving said shaft, a time-controlled shaft, common mechanism driven by said shafts, and motor-controlling devices actuated by said common mechanism for changing the speed of the motor when the contact actuating shaft is driven ahead of the time-controlled shaft.
77. In combination, contact mechanism, a shaft for operating said mechanism, a motor for driving said shaft, a time-controlled shaft, common mechanism driven by said shafts, and motor-controlling devices actuated by said common mechanism for slowing down the speed of the motor when the contact actuating shaft is driven ahead of the time-controlled shaft.
78. In combination, contact mechanism, a shaft for operating said mechanism, a motor for driving said shaft, a time-controlled shaft, differential gearing driven by said shafts, and motor-controlling devices actuated by said differential gearing for changing the speed of the motor when the contact actuating shaft is driven ahead of the time-controlled shaft.
79. In combination, contact mechanism, and an operating device for said mechanism comprising a cam having a slotted edge for engaging a part of the contact mechanism, said slot having indentations for actuating the contact mechanism proportionally to time.
80. In combination, contact mechanism, a wage-register connected with said mechanism, a source of current in circuit with said contact mechanism and wage-register, and an operating cam for said contact mechanism, said cam conformed to engage said contact mechanism to actuate said register according to wages earned.
- In witness whereof, I hereunto subscribe my name this 3rd day of June 1908.
- ARTHUR F. POOLE.
- Witnesses:
- WILLIAM J. CRUMPTON,
LYNN A. WILLIAMS.
